United States Patent Office

Des. 176,984
Patented Feb. 28, 1956

176,984

FAN UNIT

Gustav H. Koch, Springfield, Mass., assignor to Westinghouse Electric Corporation, a corporation of Pennsylvania

Application September 10, 1954, Serial No. 32,239

Term of patent 14 years

(Cl. D26—7)

FIG.1.

FIG. 2.

FIG. 3.

Fig. 1 is a perspective view of one side of a fan unit showing my new design;

Fig. 2 is a perspective view showing the opposite side of the fan unit; and

Fig. 3 is a plan view thereof.

The dominant features of the design reside in the portions shown in full lines.

I claim:

The ornamental design for a fan unit or similar article, substantially as shown and described.
